ELECTRIC SHAVER

John F. Wahl, Sterling, Ill., assignor to Wahl Clipper Corporation, Sterling, Ill., a corporation of Illinois

Application April 3, 1958, Serial No. 50,321

Term of patent 14 years

(Cl. D22—3)

Fig. 1 is a front elevational view of an electric shaver embodying my new design, the rear thereof being substantially similar in appearance;

Fig. 2 is a side elevational view thereof looking from the right of Fig. 1;

Fig. 3 is a side elevational view thereof looking from the left of Fig. 1;

Fig. 4 is a bottom view thereof, and

Fig. 5 is a top view thereof.

The dotted line, partial illustration of the cord shown in Figs. 1, 2 and 3 is for illustrative purposes only.

I claim:

The ornamental design for an electric shaver, as shown and described.
